UNITED STATES PATENT OFFICE.

WINFIELD W. CONARD, OF NORRISTOWN, PENNSYLVANIA.

REINFORCEMENT FOR CONCRETE.

No. 858,153.

Specification of Letters Patent.

Patented June 25, 1907.

Application filed February 15, 1907. Serial No. 357,512.

To all whom it may concern:

Be it known that I, WINFIELD W. CONARD, a citizen of the United States, residing at Norristown, in the county of Montgomery and the State of Pennsylvania, have invented a new and useful Improvement for Reinforcement for Concrete.

My invention relates to reinforcing concrete structures and the like.

It consists in the employment of the usual rolled structural steel or wrought-iron shapes in such manner that such metal parts may be made in an ordinary structural steel or iron shop requiring the use of no special machinery or parts.

The nature and scope of my invention will be more readily understood from the following description taken in connection with the accompanying drawings forming part hereof, in which

Figure 1 is a side elevational view partly in section of a portion of a structure embodying the main features of my invention, the outline of the concrete being shown in dotted lines. Fig. 2 is a sectional plan view, taken on the line 2—2 of Fig. 1. Fig. 3 is a vertical section taken on the line 3—3 of Fig. 1. Fig. 4 is a similar view taken on the line 4—4 of Fig. 1. Figs. 5, 6, 7, 8 and 9 are sections showing various shapes that may be used as tension members in the main or cross beams and the manner of attaching the shear members thereto, and Fig. 10 is a similar view showing the use of an angle as a shear member in place of the flats shown in the other figures.

Referring to the drawings 15 is the column of any preferred form of rolled or built up section. Joined to column 15 in any desired manner is the tension member 16 which may consist of any of the usual rolled structural shapes such as channels, angles, tees, I beams, zees, or the like. Member 16 is so positioned as to be below the neutral axis of the finished concrete girder to thereby take care of the tensile stresses existing in the same. The preferred manner of connecting member 16 to column 15 consists in seating its end adjacent to the column on a connection angle 17 of the usual type or otherwise as may be found convenient and riveting or bolting thereto. Additional connection angles 18 riveted or bolted to the sides of member 16 and to column 15 may be used if desired. Riveted or bolted to member 16 at suitable intervals and preferably inclined

toward column 15 are the shear members 19 which may carry projections 20 at their upper ends consisting of angles as shown or otherwise or members 19 may simply be bent over if desired. The purpose of projections 20 is to tie members 19 into the concrete at their upper ends. The shear member 19 adjacent to the column 15 is riveted or bolted to the said column either by means of a connection angle 22 as shown or bolted or riveted directly to some other projecting flat surface of the column as is desired so as to give a strong and rigid connection between the girder and column capable of resisting the shearing stresses in the girder and the wind and other lateral forces coming upon the structure. Rods or bolts 21 may be placed in holes in member 16 to secure the better adherence of the concrete.

Supported by member 16 are the tension members 23 of the transverse or cross beams, said members 23 being so positioned and proportioned as to lie below the neutral axis of said beam to withstand the tensile stresses existing in the same when completed. Members 23 also have riveted or bolted thereto shear members 24 suitably located and inclined and if desired carrying projections 25 at their upper ends. Several of the shear members 24 adjacent to the girder and its tension member 16 are connected together at their upper ends by a tie bar 26 serving to take care of the tensile stresses existing in the completed beam.

It should be understood that the various members constituting the structure may consist of any of the usual rolled shapes used either singly, in pairs or in multiple as desired without departing from the spirit of my invention, so long as the adjoining flat surfaces of various members or of plates or angles fastened thereto are joined together by riveting or bolting in the manner well known in the art of bridge and structural steel and iron work.

Having thus described the nature and characteristic features of my invention what I claim as new and desire to secure by Letters Patent is

1. A reinforcement in concrete consisting of a column, a tension member secured thereto, and shear members secured to said tension member, the shear member adjacent to the column being secured thereto, the various parts consisting of rolled shapes of the usual types. All substantially as set forth.

2. A reinforcement for concrete comprising a column, main beam tension members carried by said column, shear members secured to the main beam tension members, the shear member adjacent the column being secured thereto, cross beam tension members supported by the main beam tension members, shear members secured to the cross beam tension members, the shear members adjacent the main beam tension member be-

ing secured together at their upper ends over the main beam tension member.

In witness whereof I have signed my name to this specification in the presence of two subscribing witnesses.

WINFIELD W. CONARD.
